UNITED STATES PATENT OFFICE.

AMBROSE N. DIEHL, OF DUQUESNE, PENNSYLVANIA.

METHOD OF AND APPARATUS FOR CLEANING GASES.

Application filed August 5, 1919. Serial No. 315,519.

To all whom it may concern:

Be it known that I, AMBROSE N. DIEHL, a citizen of the United States, and resident of Duquesne, in the county of Allegheny and 5 State of Pennsylvania, have invented certain new and useful Improvements in Methods of and Apparatus for Cleaning Gases, of which the following is a specification.

My invention relates to cleaning air and 10 other gases, and the removal of liquids or of dust and other finely divided solids contained in such gases, and while not limited to such use, more particularly relates to cleaning the combustible gases evolved in a blast 15 furnace and used in heating hot blast stoves, for firing steam boilers, and in the operation of gas engines using blast furnace gas as fuel, and for similar industrial purposes.

One object of my invention is to provide a 20 novel method of cleaning gases whereby finely divided solids or liquids in suspension in the gases are easily and quickly removed in a cheap and economical manner.

Another object of my invention is to 25 provide a novel method of cleaning gases by the use of which finely divided solids or liquids in a flowing column of gases are separated therefrom and collected, and by which the collected impurities are removed and 30 isolated and deposited out of the path of the column of gases.

Another object of my invention is to provide an improved method of cleaning gases 35 in the use of which the movement of finely divided solids or liquids carried in suspension in a flowing column of gases is arrested and retarded, and the arrested impurities are separated and removed from the traveling column of gases.

40 A further object of my invention is to provide an improved method of cleaning gases by which counter-currents are created within a traveling column of gases and are utilized in separating and removing finely divided solids or liquids from the flowing column of gases.

45 A still further object of my invention is to provide apparatus for cleaning gases of improved construction and having novel means whereby the movement of impurities such as dust or finely divided solids and liquids in suspension in a flowing column of gases is arrested or retarded and the retarded impurities are separated and removed

from the column of gases without interruption in the flow of the column of gases. 55

A further object of my invention is to provide apparatus for cleaning gases having improved means whereby the direction of movement of finely divided solids or liquids 60 in a moving column of gases is changed and controlled in removing the dust or solids from the gases.

A further object of my invention is to provide gas cleaning apparatus of improved 65 construction having novel means whereby counter-currents formed within a moving body of gases and the counter-currents are utilized in removing dust or finely divided solids or liquids in suspension in the gases 70 and whereby the dust or other solids are separated from the column of gases.

Still further objects of my invention consist in providing apparatus having the novel 75 constructions, combinations, and arrangement of parts shown in the drawings, to be more fully described hereinafter and to be particularly pointed out in the appended apparatus claims.

Referring now to the accompanying drawings, forming part of this specification, Figure 1 is a plan showing one arrangement of gas cleaning apparatus constructed and arranged in accordance with my invention and adapted for use in carrying out the method 80 forming part of my invention.

Figure 2 is a side elevation of the apparatus shown in Figure 1.

Figure 3 is a transverse sectional elevational elevation taken on the line III—III 90 of Figure 2.

Figure 4 is a sectional elevation, partly in section, showing one form of separating mechanism, as constructed and arranged and as applied for use in carrying out the method 95 forming part of this invention.

Figure 4^a is an enlarged sectional detail showing the construction of a preferred form of the screen or filter forming part of my improved apparatus.

Figure 5 is a sectional plan on an enlarged scale, of the separating apparatus shown in Figure 4, the section being taken on the line V—V of Figure 4.

The drawings show my improved apparatus applied to the gas main of a blast furnace for use in cleaning the gases evolved in the blast furnace, during the passage of the

gases from the furnace to the hot blast stoves. It will be obvious however, that the apparatus also is applicable to steam boilers or other apparatus of utilization.

- 5 In the accompanying drawings, the numeral 2 designates a gas cleaning chamber having a gas inlet 3 (Figures 4 and 5) on its lower end. The inlet 3 connects with the outlet 4 on the upper side of the gas box 5
10 which extends lengthwise horizontally below the cleaning chamber 2. The gas box 5 has a supply conduit or flue 6 connected thereto through which rough cleaned or, in some cases, raw or uncleared gases are conducted
15 into the gas cleaning chamber 2, a valve 7 on the conduit 6 providing means for shutting off the supply of gases to the gas box 5. The upper end of the cleaning chamber 2 has a gas outlet 8 therein which is connected by
20 the gas flue to a horizontally extending main clean gas flue or gas main 10.

Mounted within the chamber 2 so as to turn on a vertical axis, is a rotatable dust collector which, as shown, in Figures 4 and 25 5, comprises oppositely extending hollow arms 12, 12, having inwardly converging top and bottom sides 13 and 14 and open outer ends, a boss 15 connecting the adjacent top sides and a similar boss 16, the bottom sides. 30 (See Figures 4 and 5.) The bosses 15 and 16 have screw threaded openings therein in which the threaded ends of pipes 17 and 18 are secured to form a sectional hollow shaft for the hollow arms of the rotating collector.
35 Positioned within the cleaning chamber 2 is a stationary cylindrical screen 19 which, as shown, is formed of case metal, its surface being perforated by a multiplicity of small apertures or holes. The screen 19 is secured by the inturned flanges 21 to the bottom of the cleaning chamber 2 and its upper edge is provided with an outwardly turned flange 22 to which a detachable lid or cover 23 is secured, this cover having a 40 stuffing box 24 and gland 25 thereon, through which the section 17 of the hollow shaft extends. The lower section 18 of the hollow shaft projects downwardly through the stuffing box 26 and gland 27 on the lower side of the gas box 5 located below the cleaning chamber 2 and is mounted by its lower end in a step bearing 28 positioned beneath the gas box 5.

45 The open ends of the arms 12 have recessed flanges 12^a and in the recesses is a compressible packing material 12^b which is in contact with the inner surface of the screen 19.

50 The foraminous partition or screen 19 is covered on its outer surface preferably with a filtering medium such as a plurality of layers of loosely woven fabric or fibrous material 29. The material 29 may be metallic or non-metallic, steel wool, copper wool, flocculent or woven asbestos, and similar ma-

terials being particularly adapted for use in cases wherein the gases are highly heated, as, for example, blast furnace coke oven and producer gases. (See Figure 4^a.) Wire netting or similar woven wire fabric may be 70 employed as an envelope for the pads of steel or mineral wool and similar materials, when such materials are used in forming the filter.

A series of wraps, loosely wound, of metal 75 wire also may be substituted for the filtering medium shown in Figure 4^a and a series of wraps of woven wire fabric also may be used instead of the fibrous material 29 shown in Figure 4^a.

The upper section 17 of the hollow shaft extends upwardly through a stuffing box 30 and gland 31 provided on the elbow 32 forming part of the gas outlet 8 leading from the cleaning chamber and projects into the stuffing box 33 and gland 34 on the end of the stationary gas flue 35, which is located to the one side of the cleaning chamber 2. A worm gear 36, which is keyed or otherwise fastened on the hollow shaft, meshes with 80 the worm 37 on the worm shaft 38 and the worm shaft is coupled to the armature shaft 39 of the driving motor 40, the motor being mounted on the platform 41 positioned above the gas cleaning chamber 2. The gas flue 35 connected to the upper end of the hollow rotating shaft, extends horizontally and then vertically downward and is connected into one side of the dust collector or dust catcher 42. This flue is shown provided with a valve 43, located between the dust catcher and the upper end of the hollow rotating shaft, to afford means for stopping the flow of gases through the hollow shaft into the dust catcher 42. The dust 85 catcher is also provided with an outlet flue or pipe 44 adjacent to its upper end, the pipe 44 having a valve 45 thereon to stop the flow of gases therethrough from the dust catcher and this outlet pipe 44 is connected at one end to the inlet on the exhaust blower or fan 46, the shaft 47 of the fan being connected to the armature shaft 48 of the fan driving motor 49, and the fan and motor being mounted upon a suitable base 50 provided 90 for that purpose.

In Figure 1 of the drawings two gas cleaning units are shown, one for each of the two stoves 61, each unit having a cleaning chamber 2 and dust catcher 42 with the dust catchers connected by gas flues 44 to the single exhaust fan 46. When desired, however, independent exhaust fans 46 will be provided, one for each of the gas cleaning chambers 2.

The dust catcher 42 has a downwardly extending frusto-conical partition 51 and the space between the partition 51 and the outer shell of the dust catcher is provided with a transversely extending diaphragm or 105 110 115 120 125 130

partition 52. The upper end of the partition is secured to an annular plate 53 which is fastened on its outer marginal edge to the shell of the dust catcher 42. The bottom 54 of the dust catcher is conical and has an outlet opening 55, through which the finely divided solids or liquids separated from the body of gases and collected in the bottom of the dust catcher, are removed from time to time. The valve 56 on the outlet 55 provides means for closing the outlet opening, except when removing the collected materials from the bottom of the dust catcher.

An overhead gas main 57 leads from the blast furnace or a plurality of furnaces, and branch pipes 6 leading from the top of the gas main 57 connect the rough gas main 57 with each inlet on each gas box 5, these gas boxes leading to the inlets on the cleaning chamber 2. The branch gas flue 10 from the gas outlet of the cleaning chamber 2 connects with a vertically extending pipe 58 which opens at its lower end into the gas box 59 of the gas burners 60 on the hot blast stoves 61 and its upper end 62 opens into a clean gas main 63 which extends horizontally parallel with the rough gas main 57, the gas main 63 delivering the cleaned gases to the gas engines, steam boilers, or other place of use.

The outlet 64 on the exhaust fan or blower 46 is connected to a branch gas main 65 which, as shown, connects into the rough gas main 57 and has a branch 66 which leads to a place of use for the gases withdrawn through the cleaning chambers in removing the dust from the gases passing through the cleaning chamber.

In carrying out my improved method of cleaning gases with apparatus constructed and applied for use, as shown, the rough or uncleanned gases are caused to pass from a blast furnace through the rough gas main 57. The uncleanned gases flow from the rough gas main 57 through the branch pipes 6 into the gas box 5 located below the gas cleaning chamber 2 and, rising upwardly within the chamber 2 pass through the screen 19 and fibrous filter or dust retarding medium 29. The filtered gases then rise upwardly and pass through the outlet 8 of the cleaning chamber into and through the branch pipe 10 into the clean gas main 58. (See Figures 1 and 2.) The cleaned gases are then delivered by the gas main 58 to the box 59 for the gas burners on the hot blast stoves and any other desired place of use.

The gases pass through the screen 19 under a pressure of several ounces and the surface of the screen is made sufficiently large to not obstruct or retard the flow of gases through to a great or harmful extent.

The motor 40 is started to rotate when the apparatus is put into use so as to turn

the hollow shaft and the collector secured on the hollow shaft which is located within the cylindrical screen 19 in the cleaning chamber 2, and the motor 49 also is started in operation to turn the blades of the exhaust fan 46 and in this way create a partial vacuum within the hollow shaft and the conduit leading from the cleaning chamber 2, to the inlet of the exhaust fan 46.

The gases will readily pass through the foraminous screen 19 and filtering medium or covering therefor but the travel of any finely divided solids or fluids in the gases, while not necessarily stopped, will be hindered or retarded in passing, and will collect upon the surfaces of the filtering medium. The ends of the rotating collector arms will traverse the inner surface of the screen and, as the slot in the outer end of each arm 12 sweeps past a given point on the screen 19, a counter-current is created in the column of gases and any finely divided deposits on the screen and filtering medium at such point will be removed by the collector arms and will be carried into the hollow collector arms 12.

Owing to the partial vacuum created and maintained within the hollow arms 12 of the collector, the velocity of the reversely flowing portions of the gases entering the hollow arms is very greatly increased and in withdrawing the gases through the screen 19, into the hollow collector arms 12 and hollow shafts 17, retarded and arrested particles of finely divided solids or liquids on the screen and screen covering 29 are taken up and withdrawn from the screen and are carried through the hollow shaft into the lower part of the dust catcher 42. The gases withdrawn through the hollow arms are heavily laden with the concentrated dust, and finely divided solids or liquids removed from the screen surface, and in traversing the spiral path within the dust catcher 42 the major portion of the impurities will become deposited in the bottom of the dust catcher. The gases withdrawn in this way from the cleaning chamber 2 into the dust catcher 42 rise upwardly and pass through the outlet on the dust catcher into and through the flue 44 and the exhaust fan 46. As the discharge side of this exhaust fan delivers the gases under pressure, gases passing from the fan will be forced through the conduit 64 and returned to the rough gas main 57 or other main, in which the pressure is at or somewhat below that of the gases from the fan 46.

It has been found by experiment that under normal conditions in treating blast furnace gases by my improved method, the quantity of gases withdrawn through the collector arms is very small relative to the large volume of gases passed through the screen,

and on account of the increased velocity of the withdrawn gases, the impurities collected on any given portion of the screen or filter are removed in much less time than 5 is required for them to become deposited on the screen or filter.

The gases are freed of the finely divided impurities carried in suspension in passing through the screen and the cleaned gases 10 are then delivered to the gas burner of the stoves or other place of use.

When the so cleaned gases are to be used for fuel in operating gas engines or in cases where further or more complete removal of 15 the solids is necessary the gases will be again passed through another gas cleaning unit or series of units constructed in the manner which has been described, or such gases may be passed through a wet gas washer, or other 20 form of washer as desired.

The operations which have been described are carried out continuously, so long as the gas supply is maintained, or until it is desired to stop the operation of the apparatus. 25

Where there is a very large supply of gas to be cleaned which is to be used in a large number of different localities, the gas cleaning units, preferably, will be made relatively 30 small and a series of such units will be employed and independently operated, one fan, preferably, being employed with the plurality of cleaning chambers.

By the term "finely divided materials" as 35 used in the claims and elsewhere herein, is meant finely divided solids and liquids and any other impurities carried in suspension in the gases and capable of being removed with my improved apparatus.

40 The advantages of my invention will be apparent to those skilled in the art. By employing my improved method the dust, liquids, or other finely divided materials contained in the gases are rapidly and efficiently removed and the cleaned gases will 45 contain but a small percentage of dirt or other foreign material per cubic foot of gases. The apparatus is simple and is easily kept in repair.

50 Modifications in the construction and arrangement of the apparatus may be made without departing from my invention.

The screen 19 may be divided into sections which are movable and have either a rotary, 55 oscillating or reciprocating movement. In such case the cleaning operation will not be continuous but will be intermittent. The apparatus shown is only one form of apparatus adapted for use in cleaning gases by 60 my improved method. When an intermittently operated apparatus is employed the screen may be cleaned by air, gas, steam or water. My invention is adapted for use in effecting the removal of acid or other liquids 65 from producer or coke-oven gases and

various changes in the apparatus may be made within the scope of the invention as defined in the appended claims.

I claim:

1. The method of cleaning gases which 70 consists in passing a column of gases through a screen to retard and arrest the passage of finely divided materials therethrough, reversing the direction of flow of portions of the gases through successively different 75 parts of said screen and increasing the velocity of said reversed flow to thereby remove the retarded and arrested materials from the screen, passing the withdrawn or reversed flow of gases through a separator 80 to remove the arrested materials therefrom, imparting a centrifugal whirling motion to said gases in said separator, and returning said reversed or withdrawn gases to the un-cleaned column of gases to be again passed 85 through said screen.

2. Apparatus for cleaning gases comprising a gas main and a stationary circular screen in said main through which the gases are caused to pass, said screen having means 90 for interrupting without stopping the passage of finely divided solids in the gases, means covering successively different portions of the inner surface of the screen and arranged to revolve so as to traverse 95 the entire inner surface of said screen at each revolution, means for creating a suction within the screen covering means to withdraw gases from the main and remove finely divided materials in passing through 100 the portions of the screen opposite the screen covering, means for separating the withdrawn gases from the solids contained therein, and means for returning the withdrawn gases after the solids have been separated 105 therefrom to the gas main to again pass through said screen.

3. Apparatus for cleaning gases comprising a gas main, a stationary circular screen in said main through which the gases are caused to pass, said screen having means for interrupting without stopping the passage of finely divided materials in the gases, means covering a portion of the inner surface of the screen and movable relatively thereto, arranged to traverse the entire screen surface, means for creating suction within the screen covering, means to withdraw gases from the main and remove finely divided materials in passing through the portions of the screen opposite the screen covering, means for separating the withdrawn gases from the finely divided materials contained therein, and means for returning the withdrawn gases to the gas main to be again cleaned. 115 120 125

4. Apparatus for cleaning gases comprising a gas main, a circular stationary screen in said main through which the gases are caused to pass, said screen having a permeable covering on its outer surface for 130

interrupting the passage of finely divided materials in the gases, a pair of diametrically opposite rotary hollow arms mounted within said screen, said arms having elongated slotted ends in rubbing contact with the inner surface of said screen, means for rotating said arms, means for creating suction within said arms to withdraw gases from the main and remove finely divided materials in passing through the portions of the screen opposite the slotted ends of said arms, means for separating the withdrawn gases from the finely divided materials contained therein, and means for returning the withdrawn gases to the gas main.

5. In an apparatus for cleaning gases the combination with a gas main and a foraminous circular partition having a permeable covering, of a pair of diametrically opposite rotary hollow arms mounted within said partition, said arms having elongated slotted ends in rubbing contact with the inner surface of said partition, means for rotating said arms, means for creating a suction within said arms to withdraw gases from the main and remove finely divided materials in passing through the portions of the screen opposite the slotted ends of said arms, means for imparting a whirling motion to said withdrawn gases to separate the finely divided materials contained therein from the gases, and means for returning said withdrawn gases to the gas main.

6. The method of cleaning gases which consists in passing a column of gases

through a screen to retard and arrest the passage of finely divided materials therethrough, reversing the direction of flow of portions of the gases through successively different parts of said screen and with sufficient velocity to thereby remove the retarded and arrested materials from the screen, passing the withdrawn or reversed flow of gases through a separator to remove the arrested materials therefrom, imparting a centrifugal whirling motion to said gases in said separator, and returning said reversed or withdrawn gases to the uncleaned column of gases to be again passed through said screen.

7. The method of cleaning gases, which consists in passing a column of unclean gases through a screen to retard and arrest the passage of finely divided materials therethrough, causing a reverse flow of portions of the cleaned gases through successively different parts of said screen, and increasing the velocity of said reversed flow of cleaned gases sufficiently to remove the retarded and arrested materials from the screen, passing the withdrawn or reversed flow of gases through a separator to remove the arrested materials therefrom, and returning said reversed or withdrawn gases to the uncleaned column of gases to be again passed through said screen.

In testimony whereof, I have hereunto set my hand.

AMBROSE N. DIEHL.
